UNITED STATES PATENT OFFICE.

SAMUEL F. BROOKS, OF INDIANAPOLIS, INDIANA.

BAFFLE.

Application filed October 3, 1927. Serial No. 223,537.

My invention relates to boiler baffles.

In certain types of boilers, for example where a number of sets of tubes are arranged substantially vertical between water carrying drums, it is the custom to employ a number of baffles to deflect the gases from the furnace as much as possible into contact with the entire outer surface of the tubes. These baffles are arranged longitudinally of the tubes and generally are provided with smaller transverse baffle extensions to increase the deflection of the hot gases as they pass from one gas passage into the other.

The principal object of my invention is to provide an improved baffle of this type.

Another object is to provide a baffle construction whereby the transverse baffle extension can be quickly replaced.

Another object is to provide a baffle adapted to be applied or removed in sections to facilitate repair and the like.

Another object is to provide an improved baffle extension by means of which expensive special large tile pieces may be done away with.

Other objects and features of the invention will be apparent from a consideration of the detailed description taken with the accompanying drawings, wherein

Fig. 1 is a schematic sectional view showing the application of my invention to a standard type of tube boiler;

Fig. 2 is a sectional view taken along the line 2—2 of Fig. 1, looking in the direction of the arrows;

Fig. 3 is an elevational view of one form of baffle tile;

Fig. 4 is an end view thereof;

Fig. 5 is a side view;

Fig. 6 is another form of tile;

Fig. 7 is an end view, and

Fig. 8 is a side elevational view.

The baffle of my invention is adapted to be applied to various types of boilers, but is here shown attached to a well known type of boiler consisting of tubes 10—10 with the usual connecting drums 11—11. A pair of baffles is provided longitudinally of the tubes so as to result in the production of a number of gas passageways 12, 13 and 14, respectively, the gases being deflected around these passageways by means of the baffles.

In the preferred form of baffle, I employ sectional blocks or tiles 16 having their top and bottom provided with grooves 16^a and projections 16^b, respectively, while the edges

are off-set in the manner shown so that the tiles may be set side by side in overlapping relation. These tiles are formed with recessed faces 16^c or with plain faces as shown in Fig. 6. The tiles are arranged side by side and one row above the other to the desired height depending upon the construction of the boiler in which they are used.

At a proper place on the composite baffle, a baffle extension is provided for the purpose of still further deflecting the gases into contact with the tubes at right angle with the passageway through which the gases are flowing. This transverse baffle projection is made removable from the baffle as a whole and contains novel features which will now be described.

A number of tiles 17 are provided of angular shape but in other ways corresponding with the standard tile section 16. These tiles 17 are laid side by side to form a row of tiles in the same manner as for the standard type of tiles. Two such rows are formed faced oppositely to each other with a narrow space or slot between them into which plain tile strips 18 are inserted in the manner shown, the plain tile being held by the angular projection on the angular tiles 17 and projecting upwardly a distance above the baffle wall, depending upon the deflecting action desired. Above this baffle extension, the tiles 16 are again laid to produce the standard baffle formation, with the exception that the tiles are reversed with respect to the tiles below the projection. This reversal is necessary to take care of the grooves and projections 16^a and 16^b and by so reversing the tiles, a single type of angular tile 17 can be used, whereas if the reversal were not made, it would be necessary to provide two types of angular tiles 17, namely one provided with a groove end and the other with a projection end.

With this baffle construction there are no expensive angular tiles which must be replaced whenever accidents or overheating cause a breaking of the baffle extension. All that is necessary, is to replace the plain tile, and even should it be necessary to replace any portion of the angular tile strip, only a single type of tile is necessary and that of a standard height, independent of the particular furnace or boiler into which it will be placed.

Another advantage is that the equipment is standard in the sense that it can be placed in any boiler, the tile 17 being the same

whether the boiler is large or small. The only change made is in the length of the plain tile 18, that is to say, the amount which it projects from the main baffle wall.

5 Where the width of the boiler itself varies, this is made up for by inserting a greater number or smaller number of plain tiles 18.

10 Although a specific form of baffle is shown, it is not desired to restrict the invention to this particular form, and no limitation is made except as defined in the appended claims.

15 What I claim as new and desire to secure by United States Letters Patent is:

1. In a boiler having a plurality of drums with tubes connecting the same, a baffle disposed longitudinally of the tubes and comprising overlapping tiles with a deflecting projection thereon said deflecting projection comprising oppositely faced rows of angular tiles, with a plurality of plain tiles removably held between the angular tiles.

2. In a boiler a plurality of drums with tubes connecting the same, a baffle disposed longitudinally of the tubes, a pair of angle sections forming a part of the baffle and

running transversely of the same, and a plain tile insert held between the angle sections, and constituting a baffle extension.

3. A boiler baffle comprising a pair of relatively flat sections disposed in a single plane, said sections terminating in opposed angle portions with a space therebetween, and a section of plain tile disposed between the flat section and held by the angles, so as to constitute a baffle extension from the boiler baffle proper.

4. A boiler baffle consisting of two relatively flat refractory sections separated from each other and disposed end to end, transverse portions of angular form on each of the flat sections, and a plain tile projection held between said angular portions.

5. The combination with a vertical boiler baffle of a relatively short, generally horizontal baffle extension, said extension comprising two rows of oppositely faced relatively short legged angles, and an insert between them of flat projecting tile sections.

In witness whereof, I hereunto subscribe my name this 10th day of September, 1927.

SAMUEL F. BROOKS.
